(57) **CLAIM**

I claim the ornamental design for a bottle, as shown and
described.

DESCRIPTION

FIG. 1 is a front elevation view of my new design with the
backside being a mirror image thereof;

FIG. 2 is a side elevation view with the right and left side
being identical;

FIG. 3 is a top plan view thereof, shown at an enlarged scale;
and,

FIG. 4 is a bottom plan view.
